WILLIAM H. SELLEY, OF NEW BEDFORD, MASSACHUSETTS, ASSIGNOR TO SACO-LOWELL SHOPS, OF BOSTON, MASSACHUSETTS, A CORPORATION OF MASSACHUSETTS.

WARP-SIZING MACHINE.

Application filed July 13, 1923. Serial No. 651,193.

This invention relates to machines used in the textile industry for sizing warp yarn and commonly referred to as "slashers."

Machines of this type include a sizing tank equipped with rolls for guiding the yarn through the sizing in the tank, squeeze rolls which squeeze the surplus sizing out of the yarn, one or more drying cylinders over which the yarn passes immediately after leaving the squeeze rolls, leese rods, and a delivery roll which advances the yarn to a beam on which the yarn is finally wound. A great many strands or "ends" of yarn are run through the slasher at a time. When it is necessary to stop the machine to "count in" or "lay in" a new set of ends, the sizing hardens on the size and squeeze rolls and on the yarn which has just passed through the sizing bath. Consequently, before the machine can be started again it is necessary to wash off this hardened sizing. It is inevitable that the sizing will be washed off a section of the yarn immediately adjacent to the squeeze rolls and which has already passed through these rolls. The unsized yarn is much weaker than the sized yarn, and if the yarn from which the sizing has been washed is allowed to go through the machine in this manner, it is likely to cause a great deal of trouble in the subsequent operation of weaving due to the fact that the unsized sections of yarn are weak and consequently likely to break. It is necessary, therefore, after "counting in" a new set of ends to throw away the unsized section of yarn. Furthermore, all the yarn in the machine must be discarded with this waste section since the length of yarn between the size rolls and the delivery roll could only be saved by "piecing up." The labor involved in performing this operation obviously would cost more than the value of the yarn to be saved.

It is the chief object of the present invention, therefore, to improve machines of this type with a view to eliminating this waste of yarn.

The nature of the invention will be readily understood from the following description when read in connection with the accompanying drawings, and the novel features will be particularly pointed out in the appended claims.

In the drawings,
55 Figure 1 is a diagrammatic view showing

the various parts that guide and feed the yarn, but omitting much of the driving mechanism;

Fig. 2 is a plan view of the mechanism shown in Fig. 1, but showing the driving mechanism;

Fig. 3 is a plan view, partly in cross section, of the gearing which forms part of the driving mechanism;

Fig. 4 is a cross sectional view on the line 4—4, Fig. 3;

Fig. 5 is a sectional elevation on the line 5—5 of the mechanism shown in Figs. 3 and 4;

Fig. 6 is a side elevation showing the driving mechanism for the cylinders;

Fig. 7 is a vertical cross sectional view through the sizing tank and adjacent parts; and

Fig. 8 is a cross-sectional plan view showing certain details of the driving mechanism for the cylinders.

Referring first to Figs. 1 and 2, the strands of yarn are drawn from supply rolls or section beams, indicated at 2, and they pass over a guide roll 3, under a takeup roll 4, and over guide rolls 5 and 6 to an immersion roll 7 which is mounted to rotate freely in the sizing tank 8. The yarn next passes between a size roll 9 and a squeeze roll 10, thence between another size roll 12 and squeeze roll 13, next over the large drying cylinder 14, and thence over the small cylinder 15, between the leese rods 69 and through the comb 70 to the delivery roll 16. From this roll the yarn passes to the loom beam 17 on which it is wound in readiness to be transferred to the loom.

The machine is driven through a variable speed mechanism comprising two cones 18 and 19, Fig. 2, which are connected by a belt 20. A pinion 64 mounted on the shaft of the cone 19 drives the delivery roll 16 by means of the delivery roll gear 65 which, in turn, drives the loom beam gear 66. The shaft of the delivery roll carries a bevel gear 21, driving a bevel pinion 22 which is keyed on a side shaft 23 that extends the entire length of the machine. Both the drying cylinders in the present machine are driven from the shaft 23. The driving connections between the shaft 23 and the cylinder 14 are best shown in Figs. 6 and 8, from which it will be seen that the shaft 23 carries a mitre gear 24, driving a similar gear

25 having a gear 26 secured fast thereto. This gear meshes with a pinion 27 fast on a shaft 28 to which is fixed a pinion 29 which meshes with the teeth of a ring gear bolted to the end of the cylinder 14. Similar connections between the shaft 23 and the cylinder 15 drive the latter cylinder.

At its rearward end the shaft 23 drives a pinion 32, Fig. 2, through a mitre gear connection 31, and this pinion meshes with gears 33 and 34, respectively, which are fast on the ends of the shafts which carry the size rolls 9 and 12. The construction so far described is substantially like that which has been used heretofore.

It will be observed that the yarn is fed through the machine by the sizing rolls, cylinders and delivery roll, all of which are positively driven. Also that the direction of rotation of all these parts depends upon the direction of rotation of the cone 18, and that if the direction of rotation of this cone is reversed, the entire machine will be reversed.

25 The driving mechanism of the machine is best shown in Figs. 3, 4 and 5 and comprises a pulley 36 fast on the shaft 37 on which the cone 18 is fastened, a slow speed pulley 39 which is keyed on a sleeve 40 that rotates freely on the shaft 37, and a loose pulley 38 mounted to turn freely on the sleeve 40. A pinion 41 is secured to this sleeve 40 and meshes with a gear 42 keyed to a shaft 43. A pinion 44 is mounted slidably on but is splined to the shaft 43, and when in the position shown in Figs. 3, 4 and 5, the pinion 44 meshes with and drives a gear 45 which rotates loosely on the shaft 37. Another pinion 46 which is integral with the gear 48 and turns freely on a shaft 47 mounted above the shaft 43, also meshes with the gear 45 but normally rotates idly. The pinion 44, however, is arranged to be moved out of mesh with the gear 45 and into mesh with the gear 48. At this time, therefore, the gear 45 will be driven in a reverse direction through the normally idle gears 46 and 48.

As above stated, the gear 45 is loose on the shaft 37, but it is arranged to drive this shaft in either direction through ratchet wheels 50 and 51, respectively, Figs. 3 and 4, mounted at opposite sides of the gear. That is, the gear carries two pawls 52 and 53 which are arranged to engage, respectively, with the ratchet wheels 50 and 51. A spring 54 which partially encircles the hub of the stationary arm 58 has one end positioned between two pins 55 and 56, respectively, that project from an arm integral with the pawl 52. Another spring 57 partially encircles the hub of the ratchet wheel 51 and is similarly connected with the pawl 53. By referring to Fig. 4 it will be seen that when the gear 45 is driven in a counter-clockwise

direction, carrying the pawl 52 with it, the pin 56 will drag the spring 54 along with the pawl and this dragging action will tip the pawl 52 in a counter-clockwise direction and bring it into engagement with the teeth 70 of the ratchet wheel 50. This wheel is secured to the shaft 37 so that the result is to drive this shaft in a counter-clockwise direction. If the rotation of the gear 45 now should be reversed, the pin 55 would strike the end of the spring 54 and tip the pawl 52 out of engagement with the teeth of the ratchet wheel 50, the pawl being held in this position by the drag of the spring on the pin 55. At the same time, the spring 57 would tip the pawl 53 into engagement with the ratchet wheel 51 and thus drive the shaft 37 in a clockwise direction.

For the purpose of shifting the pinion 44 into mesh with either of the gears 45 or 48, the hub of the pinion 44 is provided with a groove 49, Fig. 5, to receive a fork or shifter 60 which is carried by a rod 61 mounted to slide horizontally in the machine frame. A strong spring 62 acts on this rod in a direction to hold the pinion 44 normally in mesh with the gear 45, the movement of the rod under the influence of the spring 62 being limited by a collar 63, Fig. 3. Handles 67, 68 are provided at the opposite ends of the rod 61 so that it may be shifted conveniently by the workman.

Assuming that the parts are in the positions shown in Figs. 3 and 5, it will be seen that the machine will be driven forward at a high speed when the driving belt is on the fast pulley 36, and that the machine will be driven in the same direction at a much slower speed when the belt is on the intermediate pulley 39. If the belt is shifted to the loose pulley 38 the machine, of course, will be stopped. If, however, the belt is on the intermediate pulley 39, thus driving the machine forward at a slow speed, and the rod 61 should be moved to shift the pinion 44 into mesh with the gear 48, the motion of all the driven parts of the machine would be reversed due to the reversal of rotation of the shaft 37. The machine speed, however, would be even slower than that of the forward slow speed due to the ratio between the gears 48 and 46.

In order to eliminate the danger of pushing the reverse gearing into mesh when the belt is on the high speed pulley, or of shipping the belt from the slow to the high speed pulley when the reverse gearing is in mesh, the fork or gear shifter 60 has a lug 71 on its shank which cooperates with a safety arm 72 mounted on the vertical shipper lever shaft 73, as shown in Figs. 3 and 4. An arm 74, Fig. 2, is secured fast on the shaft 73 and is connected directly to the belt shipper fork 75 and operates it. Another arm 76 also fast on the shaft 73

is connected by means of a link 77 to a hand lever 78. A rock shaft 79 connects this lever with a similar lever 80 at the opposite side of the machine. The shipping 5 of the belt therefore is effected by the movement of either one of the hand levers 78 or 80. The safety arm 72 has three positions, as indicated in Fig. 3. It is in position *a* when the belt is on the high speed pulley 10 36; in position *b* when the belt is on the slow speed pulley 39, and in position *c* when the belt is on the idle or loose pulley 38.

It will thus be evident that when the belt 15 shipping mechanism is moved to shift the driving belt from the loose pulley 38 to the slow speed pulley 39 or to the high speed pulley 36, the safety arm 72 will be swung in a clockwise direction, Fig. 3, from the position *c* to *b* and thence to *a*. When the 20 arm is in position *a* with the belt on the high speed pulley, it effectually locks the fork 60 in its forward position, since any attempt to move the fork into position to reverse the gears will be prevented by the lug 71 striking the end of the arm 72.

It is also evident that when the reverse gearing is in mesh, the lug 71 will be in its dotted line position, Fig. 3, and that it will prevent the safety arm 72 from being moved 25 into position *a* which is necessary in order to ship the belt on to the high speed pulley.

When the direction of feeding movement or travel of the yarn is reversed, as above described, a certain amount of slack will 30 accumulate between the supply beams 2 and the sizing rolls 9 in the tank 8. This slack, however, is taken up by the heavy takeup roll 4, Figs. 1 and 7, located behind the tank 8 (with reference to the normal direction of feed of the yarn) and resting on the 35 yarn between the guide rolls 3 and 5, the weight of this roll being sufficient to draw the yarn backwardly over the guide rolls 5 and 6. The yarn thus is maintained taut 40 at all times.

After the machine has been stopped for the purpose of "counting in" a new set of ends, the sizing is washed off the size and squeeze rolls before the machine is again 45 started up, exactly as has been the practice heretofore. Incidentally, the sizing will be washed off the yarn immediately in front of the forward squeeze roll 13. Before the machine is again started up, however, the 50 immersion roll and yarn are first raised up out of the sizing tank and the machine then is reversed so that the yarn is fed backwardly across the top of the tank but out of contact with the sizing. This backward 55 feeding movement is continued until the section of yarn from which the sizing has been washed has been fed back of the immersion roll. The attendant then stops the machine, 60 replaces the immersion roll, so that it forces 65 the yarn down into the sizing bath, and

immediately starts the machine forward slowly, this last operation being performed simply by releasing the rod 61 and allowing the spring 62 to shift the pinion 44 into its normal position, where it directly drives the 70 gear 45. This results in re-sizing the washed yarn. When the machine has attained the proper speed, the attendant shifts the belt on to the fast pulley 36.

It will now be appreciated that this invention avoids the necessity for wasting a substantial quantity of yarn which otherwise would have to be thrown away due to the presence of an unsized section of yarn, as above described. Furthermore, this advantage is obtained through the use of a 75 relatively simple change in the machine. The cost of manufacture of the machine, therefore, is increased by only a trifling degree, while the annual saving in yarn realized from each machine is very substantial.

The drawings show the invention applied to a machine having two drying cylinders, but it will be understood that the number of cylinders employed is optional. While I 80 have herein shown and described the best embodiment of my invention that I have so far devised, it will be appreciated that the invention may be embodied in many forms, differing in details of construction from the 85 arrangement shown, without departing from the spirit or scope of the invention.

Having thus described my invention, what I desire to claim as new is:

1. In a yarn sizing machine, the combination of mechanism for feeding the yarn through the machine, a sizing tank through which the yarn is fed by said mechanism, means whereby the motion of said feeding mechanism may be reversed at will, and 100 means for drawing the yarn backwardly when said motion is reversed into position to be fed through said tank again upon a resumption of the forward feeding movement.

2. In a yarn sizing machine, the combination of a sizing tank, rolls for guiding the yarn through said tank, supply beams from which the yarn is drawn, a drying cylinder over which the yarn passes after leaving said tank, a delivery roll for the yarn, mechanism 105 for rotating said cylinder and delivery roll in a direction to feed the yarn through the tank, means whereby the direction of rotation of said delivery roll and cylinder may be reversed at will, and a takeup roll arranged to act on said yarn between said supply beams and said tank.

3. In a yarn sizing machine, the combination of mechanism for feeding yarn through the machine, means for applying sizing to the yarn during the feeding thereof, said mechanism including means adjustable to make said feeding movement either slow or fast, means whereby said feeding movement may be reversed, and means for preventing a 115 120 125 130

change of said feeding movement from slow to high speed while the machine is reversed.

4. In a yarn sizing machine, the combination of mechanism for feeding yarn through the machine, means for applying sizing to the yarn during the feeding thereof, said mechanism including means adjustable to make said feeding movement either slow or fast, means whereby said feeding movement may be reversed, and means for preventing the reversal of said feeding movement while said mechanism is adjusted for high speed.

5. In a yarn sizing machine, the combination of mechanism for feeding yarn through the machine, means for applying sizing to the yarn during the feeding thereof, said mechanism including a high speed pulley, a slow speed pulley and an idle pulley, each of said pulleys being adapted to receive a belt, mechanism for shifting the belt from one of said pulleys to another, means whereby the feeding movement of the yarn may be reversed, and means for preventing the shifting of said belt on to the high speed pulley while the yarn feeding movement is reversed.

6. In a yarn sizing machine, the combination of mechanism for feeding yarn through the machine, means for applying sizing to the yarn during the feeding thereof, said mechanism including a high speed pulley, a slow speed pulley and an idle pulley, each of said pulleys being adapted to receive a belt, mechanism for shifting the belt from one of said pulleys to another, means whereby the feeding movement of the yarn may be reversed, and means for preventing the reversal of said feeding movement while said belt is on the high speed pulley.

7. In a yarn sizing machine, the combina-

tion of a sizing tank, a plurality of rolls for engaging the yarn and feeding it through said tank, driving mechanism for said rolls including a reversible gearing and low speed, high speed and idle pulleys through which said gearing is driven, each of said pulleys being adapted to receive a belt, a shifter movable to reverse said gearing, and mechanism for shifting said belt from one of said pulleys to another, said shifter and said belt shifting mechanism having parts cooperating to prevent the reversal of said gearing while the belt is on the high speed pulley and to prevent the shifting of the belt on to the high speed pulley while the gearing is reversed.

8. In a yarn sizing machine, the combination of mechanism for feeding the yarn through the machine, means for applying sizing to the yarn during the feeding thereof, mechanism operable at will to reverse the feeding movement of the yarn, and means located behind said size applying means for drawing the yarn backwardly past the last named means when the direction of feed is reversed.

9. In a yarn sizing machine, the combination of a sizing tank, rolls for guiding the yarn through said tank, a drying cylinder over which the yarn passes after leaving said tank, mechanism for rotating said cylinder in a direction to feed the yarn through the tank, means whereby the direction of rotation of said cylinder may be reversed at will, whereby a reversal of the feeding movement of the yarn will be effected, and means for drawing the yarn backwardly past said tank when said feeding motion is reversed.

WILLIAM H. SELLEY.
